UNITED STATES PATENT OFFICE

143,109

DESIGN FOR A COMBINATION DESK UNIT

Scott P. Akers, Washington, D. C.

Application August 31, 1945, Serial No. 121,758

Term of patent 7 years

(Cl. D74—1)

To all whom it may concern:

Be it known that I, Scott P. Akers, a citizen of the United States, residing at Washington, in the District of Columbia, have invented a new, original, and ornamental Design for a Combination Desk Unit, of which the following is a specification, reference being had to the accompanying drawing, forming part thereof.

I claim:

The ornamental design for a combination desk unit, as shown.

SCOTT P. AKERS.
